UNITED STATES PATENT OFFICE.

DAVID WOLFSON, OF FAR ROCKAWAY, NEW YORK.

DUPLICATOR.

Application filed April 9, 1926. Serial No. 100,858.

My invention relates to duplicators of the class in which a stencil carrying drum is rolled over a flat bed, on which is placed the material to be printed.

5 The invention resides in the several novel arrangements of parts and in the automatic mechanism, by means of which the drum is made operative or inoperative as it rolls forward and backward over the bed, as 10 well as in the means employed for inking the stencil.

These and various other objects and advantages will be clearly understood from the following description and from the accompanying drawing of a preferred embodiment but it will be noted that various modifications might be made without departing from the scope of the invention.

In the drawings:
20 Fig. 1 is a side elevation of the duplicator.

Fig. 2 is a plan view.

Fig. 3 is a fragmentary side view, shown partly in cross-section.

25 Fig. 4 is a front view.

Fig. 5 is a cross-sectional side view of the drum, showing the inking mechanism.

30 Figs. 6 and 7 are cross-sectional end views of the drum, showing the inking mechanism in different positions.

Referring now particularly to Figs. 1, 2 and 4, the duplicator consists of a bed plate 10 supported between the side frames 11 and 12, which are provided with feet 13, 14, 15 and 16, on which the device rests. A shaft 17 is supported in the side frames near their rear ends and on this shaft the handle operated levers 18 and 19 are rotatably mounted. These levers are offset towards each other, as plainly shown at 20 and 21. The drum 22 is rotatably mounted on the shaft 23 and it attached, by means of the nuts 24 and 25, to the drum operating levers 26 and 27. These levers, like the handle operated levers 18 and 19, are offset towards each other and all these levers are rotatably connected on the shaft 28.

45 A handle 29 is mounted on the shaft 28 between the levers 26 and 27 and coil springs 30 and 31 are mounted on this shaft between the levers 19 and 26 and 18 and 27, respectively. The ends of these springs are inserted in holes in the levers, as plainly shown, and their action is such as to draw the pairs of levers towards each other, thus drawing the drum rearwardly.

Referring now more particularly to Fig. 3, it will be noted that the offsets in these levers are such that, when the handle is placed in the position shown in this view, the drum will be supported as shown. It will also be noted that the handle operated lever 19 abuts against the stop 32, which is secured on the side frame 11.

In this inoperative position, the drum is held in a fixed relation to the drum operating levers by means of the pin 33, which also rests against one of the levers. The arrangement of the inking device, which is in the interior of the drum and will be described later, is such as to counterbalance the drum in the position shown.

Referring again to Figs. 1, 2 and 4, two guide rails 34 and 35 are hinged on the side frames 11 and 12 by means of lugs 36, 37, 38 and 39, formed integral with the side frames, and lugs 40, 41, 42, and 43, formed integral with the guide rails. The rails hinge on pins 44, 45, 46 and 47.

The construction of these rails is such that they normally rest on the side frames and form a track for the drum when it is moved rearwardly. The front ends 48 and 49 are curved downwardly so as to raise the drum onto the rails, while the rear ends 50 and 51 are curved outwardly as plainly shown in Fig. 2. The drum 22 is provided with shoulders 52 and 53 which engage with the side rails in the manner now to be explained.

If the handle 29 is moved in the direction indicated by the arrow in Fig. 3, the shoulders 52 and 53 will engage respectively with the outwardly curved ends 50 and 51 of the rails 35 and 34 and thus move the rails outward to the position shown on Fig. 4. When the drum reaches the limit of its forward movement and disengages the rails, the rails drop to their normal position. When the drum is moved rearwardly, the shoulders 52 and 53 engage on the front ends 48 and 49, thus lifting the drum clear of the bed during its rearward movement.

The paper to be printed is placed on the bed plate 10 and is located and held in the correct position by the grip-bar 54, which extends across the bed plate. This grip-bar and its operating mechanism is shown on Figs. 2 and 3 but, for simplicity, has been omitted from the other views.

A square rocker shaft 55 is mounted on

trunnions 56 and 57 in the side frames 11 and 12 and is provided with a downwardly and rearwardly extending lever arm 58 which is engaged by a lever arm 59, formed on the 5 handle operated lever 19, when in the position shown in Fig. 3.

Two square bosses 60 and 61 extend downwardly from the rocker shaft and are each provided with a hole in which the rods 62 and 63 slide. These rods are connected at their forward ends to the upwardly extending paper guides 64 and 65, which are made integral with the grip-bar 54. Knurled screws 66 and 67 are provided in the lower 15 ends of the bosses 60 and 61 so that the rods 62 and 63 may be clamped in any desired position. The bed plate 10 is notched at 68 and 69 so as not to interfere with the adjustment of the grip-bar and paper guides.

20 A tension spring 70 is connected between a pin 71, attached to the side frame 11, and a lever arm 72, formed on the rocker shaft.

Another paper guide, consisting of a long bar 73, is provided on one side of the bed 25 plate and is adjusted by a plurality of knurled screws 74 which are threaded in the adjacent side frame. This guide is shown only in Figs. 3 and 4 and is used as a marginal guide.

30 Referring now to Figs. 5, 6 and 7, in which the inking device is shown, 22 is the drum and 23 the shaft extending therethrough. The drum is of the well known type, consisting of a perforated shell on 35 which the fabric pad and stencil are stretched, and is provided with a door through which the ink is applied to the inside of the perforated shell.

In the present device, a bail consisting of 40 a cross-member 80 and two arms 81 and 82 is rotatably mounted on the shaft 23. The arms 81 and 82 extend beyond the cross-member 80 and carry an inking roll rotating on the trunnions 84 and 85 inserted in 45 holes provided in the arms. The holes in the arms 81 and 82, through which the shaft 23 passes, are made considerably larger than the diameter of the shaft and compression springs 86 and 87 are inserted between the 50 cross-members and the shaft so as to assure positive engagement of the inking roll with the shell of the drum. To prevent these springs from buckling, guide pins 88 and 89 are riveted to the cross-member 80. One 55 end of each spring is wound around the shaft 23.

The arm 82 is prolonged and connected by means of the pin 90 to the operating lever 91, which is provided at its other end with 60 the handle 92. Directly under this handle, a notch 93 is provided which locks in a slot 94 in the drum when the inking roll engages with the stop 95. In this position, which is plainly shown in Fig. 7, the whole 65 inking mechanism is securely locked.

In Figs. 1 and 2, a counter 96 is shown. The counter lever 97 is operated each time the lever 18 descends, thus counting the sheets printed.

The duplicator is operated in the following manner:

When it is desired to apply ink to the drum, a small amount is poured through the door opening 98, the notch 93 disengaged from the slot 94 and the inking roll 83 re- 75 volved around the shell by manipulating the handle 92, which spreads the ink evenly over the interior of the shell.

The stack of paper to be printed is placed on the bed plate against the stops 64, 65 and 73 while the drum is in the position shown in Fig. 3. As the handle 29 is pulled forward, the grip-bar engages the papers, holding them securely against displacement, and the shoulders 52 and 53 spread the rails 85 34 and 35 as the drum descends. As the drum passes over the papers, an impression is made on the top sheet, but when the drum is returned, it is lifted clear of the papers by the rails now engaging the shoulders of 90 the drum. The printed sheet is removed and the operation repeated.

While I have described and illustrated a duplicator of the stencil type, it will be readily seen that a hectograph mat may 95 be employed on the drum in place of the stencil.

Having thus described my invention, what I claim as new and wish to protect by Letters Patent is—

1. In a duplicating device; a frame; a bed plate; a rotatable printing drum; a pair of toggle levers having an operating handle between their central joints and each connected at one end to said frame and at the 105 other end to said drum; and means for alternately lowering and raising said drum as it passes forwardly and rearwardly over said bed plate.

2. In a duplicating device; a frame; a bed plate; a rotatable printing drum; a pair of spring actuated toggle levers having an operating handle between their central joints and each connected at one end to said frame and at the other end to said drum; and means for alternately lowering and raising said drum as it passes forwardly and rearwardly over said bed plate.

3. In a duplicating device; a frame; a rotatable printing drum; a pair of offset toggle levers having an operating handle between their central joints and each connected at one end to said frame and at the other end to said drum; a stop secured on said frame and engaging with one of the said toggle levers; and the offsets in said toggle levers so formed that, when the said lever engages with said stop, the toggle levers will constitute a stand for supporting said drum in an inoperative position.

4. In a duplicating device; a frame; a rotatable printing drum; a pair of offset toggle levers having an operating handle between their central joints and each connected at one end to said frame and at the other end to said drum; a stop secured on said frame and engaging with one of the said toggle levers; offsets in said toggle levers so formed that, when the said lever engages with the said stop, the toggle levers will constitute a stand for supporting the said drum in an inoperative position; and an inking device so located in said drum as to counterbalance it in a predetermined position when in said inoperative position.
5. In a duplicating device; a pair of side frames; a flat bed plate attached to said side frames; a rotatable printing drum; a guide rail hinged to each of said side frames; a guide rail engaging shoulders formed at each end of said drum; cam faces formed at each end of said guide rails for alternately lowering and raising said drum on to and up from said bed plate; and means for rolling said drum over said bed plate.
6. In a duplicating device; a pair of side frames; a rocker shaft pivoted in said side frames; a paper gripping bar, having stops attached thereto, adjustably connected to said rocker shaft; a lever connected to said rocker shaft and actuated by the operating mechanism of said duplicating device.
7. In a duplicating device; a rotatable printing drum having a perforated circum-
- ference; a panel opening formed longitudinally in the circumference of said drum; means for closing said opening; a shaft passing longitudinally through said drum; a plural armed bail floatingly mounted on said shaft and having an inking roll rotatably mounted at its outer end; means for holding said inking roll in uniform contact with the inner surface of said perforated circumference; one of the arms of said bail being prolonged and having an operating lever rotatably attached thereto; and means for locking said operating lever in an inoperative position.
8. In a duplicating device; a rotatable printing drum having a perforated circum- 50ference; a panel opening formed longitudinally in the circumference of said drum; means for closing said opening; a shaft passing longitudinally through said drum; a plural armed bail floatingly mounted on 55said shaft and having an inking roll rotatably mounted at its outer end; spring means for holding said inking roll in uniform contact with the inner surface of said perforated circumference; one of the arms of 60said bail being prolonged and having an operating lever rotatably attached thereto; and means for locking said operating lever in an inoperative position whereby the inking device forms a counterweight for said 65drum.

DAVID WOLFSON.
